UNITED STATES PATENT OFFICE.

FRANK T. KNIGHT, OF COLUMBUS, GEORGIA.

RAILWAY CONTROLLING APPARATUS.

1,247,546.

Specification of Letters Patent. Patented Nov. 20, 1917.

Application filed June 10, 1914. Serial No. 844,264.

To all whom it may concern:

Be it known that I, FRANK T. KNIGHT, a citizen of the United States, residing at Columbus, in the county of Muscogee and 5 State of Georgia, have invented new and useful Improvements in Railway Controlling Apparatus, of which the following is a specification.

This invention relates to improvements 10 in railway controlling apparatus and has particular application to electrically controlled train stopping and speed regulating apparatus, the present invention being in the nature of an improvement over the apparatus disclosed in my Patent Number 1,145,320, issued July 6, 1915.

In carrying out the present invention, it is my purpose to provide electrically controlled railway controlling apparatus where- 20 by, under certain conditions, the propelling power of the car will be cut off and the brakes applied to bring the train to a standstill in the event of the same entering the danger zone and whereby, under certain 25 other conditions, the propelling power of the motor car will be cut down in the event of the car traveling under power.

It is also my purpose to provide train stopping apparatus of the class described 30 wherein the power controlling mechanism will act independently of the stopping mechanism.

A further object of my invention is to provide electrically controlled railway controlling apparatus which will operate effectively and efficiently under all weather conditions, which may be installed and maintained at a minimum expense and wherein the speed controlling mechanism 40 will be under the direct influence of the propelling fluid of the motor car so that such mechanism will remain inactive when the motive fluid is cut off or cut down to the proper volume.

With the above and other objects in view, the invention consists in the construction, combination and arrangement of parts hereinafter set forth in and falling within the scope of the claim.

In the accompanying drawings:

Figure 1 is a diagrammatic plan view of railway controlling apparatus constructed in accordance with the present invention.

Fig. 2 is a fragmentary cross sectional view through the trackway showing the

relative positions of the track instruments and the car carried device under the influence thereof.

Fig. 3 is a top plan view of the same.

Fig. 4 is a fragmentary sectional view 60 through the trackway showing the track instrument employed at grade crossings and similar places for cutting down the speed of the train or car.

Fig. 5 is a fragmentary side elevation of 65 the locomotive showing the controlling valve of the stopping mechanism and the speed reducing mechanism.

Fig. 6 is a horizontal sectional view 70 through the casing of the speed reducing mechanism, the latter being shown in top plan.

Referring now to the drawings in detail, A designates a trackway which, in the present instance, is divided into sections or 75 blocks. Located to one side of the trackway at the entrance to each block is a semaphore 1 of any suitable construction and operated in any desired manner.

Also located upon the side of the trackway with the semaphores 1 and disposed adjacent to the entrance of each block is a track instrument 2. In the present instance, each track instrument comprises a base plate 3 bolted or otherwise secured to the upper 85 surfaces of the ties in proximity to the adjacent semaphore 1, a vertical supporting plate 4 having the lower end thereof secured to the base plate 3 and electromagnets 5 and 6 fastened to one face of the supporting 90 plate 4 and projecting toward the adjacent line of rails of the trackway. These electromagnets 5 and 6 are spaced apart in parallelism and each has the substantially rectangular pole face having the longitudinal 95 dimension thereof disposed in a vertical plane. The magnets 5 and 6 are so wrapped or wound that the pole faces thereof are unlike, the pole of the magnet 5 being the south pole, while that of the magnet 6 is 100 the north pole. In this embodiment of my invention, the windings of the magnets 5 and 6 are connected in an electric circuit 7 including a suitable source of electrical energy as a storage battery 8 and a circuit 105 closer 9. This circuit closer is under the control of the signal blade of the adjacent semaphore and when the signal blade is in clear position the circuit closer holds the circuit 7 open and the magnets 5 and 6 de- 110

energized, while when the signal blade moves to danger position the circuit closer is actuated to closed position and the magnets energized. The supporting plate 4 of each track instrument is preferably reinforced by means of a brace bar 10 having the upper end thereof fastened to the rear face of the plate and the lower end secured to the supporting plate as clearly illustrated in Fig. 2 of the drawings.

10 In the present instance, I have shown the car carried mechanism as installed in a steam driven locomotive and in this connection I wish it to be understood that this mechanism, in its useful application, is not limited to use in conjunction with steam driven locomotives, as the same may be installed in electrically operated motor cars. 15 11 designates the throttle valve lever by means of which the throttle valve may be manipulated to control the flow of steam from the steam space of the boiler to the drive cylinder 12 of the locomotive. Disposed in proximity to the throttle valve lever 11 is a motor 13 comprising a cylinder 14 and a piston 15 mounted within the cylinder and capable of sliding movement therein. Connected with the piston 15 and projecting outwardly of one end of the cylinder is a piston rod 16 and to the outer end of the piston rod is fastened one extremity of a chain 17 or other flexible element. The opposite extremity of the chain 17 is connected to one limb of a bell crank lever 18 pivoted upon the throttle valve lever 11 and having the opposite limb thereof pivoted to the actuating rod of the latching dog of the throttle lever. B designates the brake pipe or train line air pipe of the air 20 brake system of the train and leading from such pipe is a branch pipe 19 connected with one end of the cylinder 14 of the motor 13 and adapted to establish communication between such cylinder and the brake pipe. Located in the branch pipe 19 and controlling communication between the cylinder of the motor 13 and the brake pipe is a valve 20 secured to one side of the locomotive frame immediately behind the pilot and having the stem thereof disposed in a vertical plane. Connected with the upper end of the stem of the valve 20 and projecting outwardly therefrom is a lever 21 normally extending at right angles to the path of travel of the motor car. In this position of the handle, the valve 20 is closed and communication between the brake pipe and the motor 13 cut off so that the throttle valve is under the complete control of the engineer. Formed 25 in the outer end of the lever 21 is a vertical bore 22 and passed through such bore is a vertical pin 23 having the lower end thereof screw threaded to receive a nut 24 and the upper end formed with an angular head 25. Secured to certain of the sides of the head

25 and projecting outwardly therefrom are electromagnets 26, 27 having the poles thereof elongated and disposed in an arc. These magnets 26 and 27 are wound in such manner that the poles thereof are unlike, 70 the pole face of the magnet 26 presenting a north pole, while that of the magnet 27 presents a south pole and the windings of these magnets are connected in series in an electric circuit 28 including a suitable source 75 of energy as a storage battery 29 located within the cab of the locomotive. This storage battery 29 is disposed within a casting or housing 30 having a cover normally locked so that tampering with the battery 30 and disturbing of the connections between the circuit wires and the battery by the train crew is eliminated. If desired, the wires of the circuit 28 may be inclosed in conduits. Normally, the portion of the head 25 between the electromagnet projects toward the front of the motor car so that as the car passes a track instrument the magnet 26 is adjacent to the pole faces of the magnets 5 and 6. 85

In practice, when the signal blade goes to danger position, the circuit 7 of the magnets 5 and 6 of the adjacent track instrument is closed thereby energizing such magnets so that the latter set up a magnetic field or 95 flux. Should a train attempt to pass the danger signal the poles of the magnets 5 and 26 of the track instruments and car carried mechanism respectively will be brought into engagement with each other, 100 incident to such poles being unlike and in the swinging movement of the head 25 under the action of the magnets 5 and 26, the poles of the magnets 6 and 27 attract each other and coat with the magnets 5 and 26 to 105 hold the head 25 stationary. In this holding of the head the lever 21 swings rearwardly, incident to the continued movement of the train, thereby opening the valve 20 so that the air flows from the train line air pipe B 110 into the cylinder 14 of the motor 13. As the air enters the cylinder of such motor the piston 15 is actuated and exerts a pull upon the chain 17. In the initial movement of the piston the bell crank lever 18 is swung to 115 release the latching dog of the throttle lever from engagement with the teeth of the quadrant and in the further movement of the piston within the cylinder of the motor 15 the throttle valve lever is swung to closed 120 position so that communication between the boiler and the drive cylinders of the locomotive is cut off.

The cylinder 14, adjacent to the end of the path of movement of the piston 15 under the action of the air, is formed with an exhaust port 31 whereby communication is established between the brake pipe and the atmosphere immediately succeeding the closing of the throttle valve so as to effect 130

a reduction in the train line air pipe and so cause an application of the brakes to the wheels.

Located in the circuit 28 is a pole changer 32 of any suitable construction connected through the medium of a link 33 with the lever of the valve 20. By means of this construction, it will be seen that immediately succeeding the opening of the valve under the action of the lever 21 the pole changer 32 will be actuated to reverse the connections between the battery 29 and the magnets 26 and 27 thereby reversing the polarity of the latter so that the same will be repelled by the magnets 5 and 6 of the track instrument. Thus, the magnets 27 and 26 are relieved of the influence of the magnets 5 and 6 respectively of the track instrument automatically, thereby preventing sticking.

At this point, attention is called to the fact that the magnet 26 comes into the influence of the magnet 5 initially as the train passes the track magnets and these coacting magnets 5 and 26 act to swing the head 25 initially and in this swinging of the head the magnets 6 and 27 are brought within the influence of each other to coöperate with the magnets 5 and 26 to complete the swinging of the head and hold the head stationary so that the lever 21 may be swung as the train passes the track magnets. This operation will be better understood by referring to Fig. 3 of the drawings wherein the arrow indicates the direction of travel of the train and the letters N and S the polarities of the magnets.

In some instances, particularly at grade crossings and analogous places, it is required by the rules and regulations of the railroad that the propelling power of the motor car shall be cut down so that the speed of the car or train will be decreased as such train passes over the crossing or like point and in order to automatically cut down the flow of steam from the boiler to the engine cylinders, in the event of the engineer neglecting to properly manipulate the throttle valve when the car is passing the crossing, I employ a speed reducing mechanism which is electrically controlled and under the direct influence of the propelling fluid of the motor car. In the present instance, this speed reducing mechanism is substantially identical to that disclosed in my copending application, hereinbefore referred to, and comprises a substantially rectangular casing 52 secured to the bed frame of the locomotive in advance of the forward truck and below the valve 20. The outer side wall of the casing 52 is preferably hinged so that the same may be thrown to active position when it is desired to obtain access to the interior of the casing and formed in such movable wall is a slot 54. Suitably secured

to the slot 54 is a guide 55 dovetailed in cross section and slidably mounted within the guide is a saddle 56. Fast to the saddle 56 is a valve 57 connected by means of a flexible hose 58 with a source of fluid supply such, for instance, as the main air reservoir of the air brake system. Leading out of the casing of the valve 57 is a flexible pipe 59 leading into one end of a cylinder 60 of a fluid motor. Slidably mounted within the cylinder 60 is a piston 61 and connected to the piston is a piston rod 62 projecting outwardly of one end wall of the cylinder. Connected with the outer end of the piston rod 62 is one end of a chain 63 having the other extremity thereof connected with one limb of a bell crank lever 64 pivoted upon the throttle valve 11 and having the opposite limb connected with the actuating rod of the latching dog of the throttle valve lever. It will be noted that the cylinder 60 is one half the length of the cylinder 14 of the motor 13 so that the piston in the cylinder 60, when actuated, will move the throttle valve lever to a position to half close the throttle valve and so cut down the volume of fluid passing to the drive cylinder of the locomotive. Secured to the bottom wall of the casing 52 in parallelism with the guide way 55 is a steam cylinder 63' having one end connected by way of a pipe 64 with the steam chest S of the drive cylinder 12 of the locomotive and slidably mounted within the cylinder 63' is a piston having the piston rod 66 projecting outwardly of the end of the cylinder opposite to that connected with the steam chest. Upstanding from the lower wall of the casing 52 at a point approximately centrally of the space between the cylinder 63 and the guide 55 is a support 67 upon which is mounted for swinging movement a cross arm 68 having one end connected through the medium of a pin and slot connection 69 with the outer extremity of the rod 66 and the opposite end connected through the medium of a pin and slot connection 70 with a pin uprising from the saddle 56. By means of this construction, it will be seen that when the throttle valve is wide open the steam entering the steam chest S from the bottom of the boiler will slide the piston 65 within the cylinder 63' and so move the piston rod 66 outwardly of the cylinder thereby swinging the cross arm 68 with the effect to move the saddle 66 along the guide 55 toward the outer wall of the casing 52. The stem of the valve 57 is equipped with a horizontal handle 71 which projects outwardly of the casing 52 through the slot 54, when the valve is actuated by the piston 65 and the cross arm 68, and formed in the outer end of the handle 71 is a vertical bore 72 within which is pivoted a pin 73 having the lower end thereof threaded to

with a triangular shaped head 75. Fastened to the opposite sides of the head 75 and projecting outwardly therefrom are electromagnets 76 and 77 similar to the magnets 26 and 27, hereinbefore described with reference to the stopping mechanism. These magnets 76, 77 are connected in an electric circuit 78 including a suitable source of electrical energy as the battery 29 and a pole changer 79. The pole faces of the magnets 76 and 77 are elongated and disposed in an arc and the magnets are so wound that the poles thereof are unlike. Normally, the apex of the head 75 extends longitudinally of the trackway.

At the crossing or similar point, I employ a track instrument 80 identical in construction to the instrument 2 hereinbefore described. The supporting plate of the track instrument 80 is relatively short as compared with the height of the plate of the instrument 2 and the magnets of the instrument 80 are connected in a normally closed electric circuit 81 including a suitable source 25 of energy as a battery 82. The poles of the magnets of the track instrument 80 are disposed in a plane below the plane of the poles of the magnets 5 and 6 and coincident with the plane of the magnets 76 and 77. Should 30 a train or car pass the track instrument 80 with the throttle valve wide open, the pole faces of the magnets 76 and 77 on the outer end of the handle 71 of the valve 57 will be drawn into engagement with the pole faces 35 of the magnets of the track instrument 80 and succeeding such engagement the magnets 76 and 77 are held as the train continued in its path of travel and in the continued movement of the train a pull is exerted upon 40 the handle 71 thereby opening the valve 57 to establish communication between the cylinder 60 and the source of fluid supply by way of the pipe 58, the valve casing and the pipe 59, whereby the piston within the cylinder 60 will be actuated to cut down the flow of steam to the engine cylinder. The pole changer 79 is connected through suitable mechanism with the handle 71 of the valve 57 and during the opening of the valve 45 50 the pole changer is actuated to reverse the connection between the battery and the magnets 76 and 77, thus changing the polarity of the latter so that the same will be released by the magnets of the track instrument 80.

On the other hand, should the engineer cut off the flow of steam to the drive cylinders of the engine, when approaching the crossing, the flow of steam to the cylinder 63' will be cut off so that the saddle 56 upon

the guide 55 will be restored to normal position and in order to restore the same to normal position automatically and hold the same in such position when the throttle valve is half open or less than half open, I 65 employ, in the present instance, a coiled contractile spring 83 having one end fastened to the rear end of the saddle and the opposite end secured to the adjacent side wall of the casing.

From the foregoing description taken in connection with the accompanying drawings, the construction and mode of operation of my invention will be readily apparent. It will be seen that I have provided an automatic train controlling system whereby the train will be brought to an immediate stop in the event of the same entering the danger zone, while the flow of steam to the drive cylinders of the engine will be cut 80 down in the event of the engineer passing a grade crossing or other like place with the throttle valve wide open.

While I have herein shown and described one preferred form of my invention by way 85 of illustration, I wish it to be understood that I do not limit or confine myself to the precise details of construction herein described and delineated, as modification and variation may be made within the scope of 90 the claim without departing from the spirit of the invention.

Located in the branch pipe 19 between the brake pipe B and the valve 20 is a cut off cock 84 provided with a lock 85 whereby the 95 cock may be locked in open position so as to prevent closing thereof by the train crew. Similarly, a cut off cock 86 is located in the pipe 64' between the cylinder 63' and the steam chest S and such cock 86 is equipped 100 with a lock 87 whereby the cut off cock may be locked in open position.

I claim:

In apparatus as described a valve, magnetic poles operatively connected with the 105 valve, and connected with a source of electric current, a pole changer located in the last mentioned connection and operatively connected with the valve and other magnetic poles adapted to be contacted by the first 110 mentioned poles, the last mentioned poles being connected in an open circuit, with a source of electric current and means for closing the last mentioned circuit.

In testimony whereof I affix my signature 115 in presence of two witnesses.

FRANK T. KNIGHT.
